UNITED STATES PATENT OFFICE.

ARTHUR G. FILMER, OF GLOVERSVILLE, NEW YORK.

LEATHER-FINISHING MACHINE.

No. 920,304.

Specification of Letters Patent.

Patented May 4, 1909.

Application filed August 29, 1908. Serial No. 450,899.

To all whom it may concern:

Be it known that I, ARTHUR G. FILMER, a citizen of the United States, residing at Gloversville, in the county of Fulton, State of New York, have invented certain new and useful Improvements in Leather-Finishing Machines, of which the following is a specification.

My present invention relates to machines 10 used for glazing, rolling, pebbling or glassing skins and leather.

The object of my invention is to provide certain improvements in machines of this character whereby the output of the machine 15 may be increased, and whereby the liability of tearing and ruining skins and leather may be greatly diminished.

To this end, my invention comprises an improved work-bed for holding the skins or 20 leather during treatment, this work-bed being so constructed and arranged as to insure a uniform and even pressure of the glazing or rolling tool throughout the entire stroke of the rocker arm of the machine.

25 The characteristic features of my invention will be better understood by reference to the accompanying drawings, wherein—

Figure 1 is a side elevation of a complete machine equipped with my improved work-bed; Fig. 2 is a side elevation of the work-bed; Fig. 3 is a plan view of the same; and Figs. 4 and 5 are respectively front and rear end elevations of the bed.

The framework of the glazing or rolling 35 machine comprises suitable uprights 1 and 2 supporting a tread 3, on which runs a rocker 4 carrying a rocker-arm 5. The end of this rocker-arm 5 is pivotally connected with a tool carriage 6, at the lower end of which the 40 glazing or rolling cylinder 7 is suitably mounted. A pitman 8, rigidly connected with said tool carriage, engages with a crank-pin 9 carried near the periphery of a wheel 10, driven at uniform speed as by a belt on a 45 pulley 11. The elements above mentioned are so related that when wheel 10 revolves the tool 7 is caused to travel along a work-bed with a substantially straight-line motion during the down stroke, but moves upward 50 through a curved path during the return stroke. Suitable springs 12 and 13, acting through a link 14, hold the rocker 4 firmly against its tread 3. A resilient member 15 anchors the rocker 4 to the tread 3 and prevents 55 displacement. So much of the ma-

chine shown in Fig. 1 is old and well-known, and the novelty of the present invention resides particularly in the work-bed, whereby the skin or hide is held against the reciprocating tool 7.

My improved work-bed comprises a base 16 of well seasoned hard wood, longitudinally grooved to receive a steel trunnion 17. The latter supports a bed 18, preferably of tough fibrous wood, carrying a smooth iron bed-plate 19. This bed-plate 19 is permanently secured to the wooden bed 18 by two rows of screw bolts 20 having nuts 21 countersunk into the projecting or under-cut edges of the bed, as shown in Fig. 4. These bolts 20 are, 60 however, long enough to extend down through and lock with rectangular iron strips 22 and 23 running along the upper edges of the base 16. The strips are rigidly secured to the base by bolts 24 (see Fig. 2). Blank 65 nuts 25 serve as spacers to hold these strips well above the surface of base 16, thereby permitting easy manipulation of nuts 26 and 27, whereby the screw bolts 20 are locked to the strips. The base 16 is provided, at its 70 front or upper end with a lifting-jack 28 and with two anchoring bolts 29 and 30, all carried by a heavy block 31, which is cut away near its ends to form inclined surfaces 32 and 33. The anchoring bolts 29 and 30 engage 75 with a steel bar 34 running through the base 16, and they serve not only as anchors, but also as means for tilting the base with respect to the block 31. At the other end of the base 80 16 is a second jack 35 passing through and supported by a second block 36. Anchoring means is also provided, consisting of a bolt 37 having an eye let into a recess in base 16 and engaging with a transverse steel bar 38. Anchor 37 and jack 35 lie in line along the 85 axis of the bed and so do not interfere with the tilting operation as effected by anchors 29 and 30 at the other end of the base.

The utility of the inclined surfaces on blocks 31 and 36 will be apparent by reference to Fig. 1. Beneath the base 16 is a movable frame 39 actuated by a crank 40 attached to a screw-shaft 41. This frame 39 has inclined surfaces for engagement with those on the blocks. By turning the crank 100 105 the entire work-bed can be raised or lowered and thereby adjusted with respect to the thickness of the skin, or the degree of pressure to be applied by the working tool. It will be understood that the skin to be oper- 110

ated upon lies across the work-bed and is pressed or rolled at each downward movement of tool 7. A leather strap 42 may be stretched lengthwise along the bed-plate to form a suitable working surface, being held taut by a T-plate 43 let into a slot in the bed 18 and adjusted by means of a screw 44 engaging with the end of trunnion 17.

From a consideration of the method of 10 curing bed 18 to base 16 it will be seen that by proper adjustment of the nuts on bolts 20, it is possible to tilt the bed about trunnion 17 and so change the angle of the work surface with respect to the path of the rolling 15 or glazing tool. But furthermore, by tightening some bolts more than others it is possible to twist and bend the bed 18 and bed-plate 19 in irregular manner, and so produce 20 a warped surface on which the working tool a warped surface on which the working tool 25 may run. The particular advantage of this arises from the fact that in most machines of this type the rolling or glazing tool does not run in a perfectly straight line, and the skins on the work-bed do not receive uniform 30 treatment throughout. If the pressure is just right at one point it may be too little or too much at another, and the skin comes out either incompletely treated or else torn by excess pressure. Sometimes this deviation 35 from a straight-line motion is due to imperfections or wear in the rocker 4 and its tread 3; sometimes to improper proportioning of the several parts which should coact to produce the straight motion, and sometimes 40 to inaccurate assembly of the several parts. In all of these cases the tool presses unevenly on the work and the results are unsatisfactory. But according to the present invention, the work-bed can be so 45 warped and adjusted as to compensate for these irregularities, and thereby keep the skin under steady pressure throughout the stroke: also, it can be adjusted to compensate for wear or other change in the work-bed itself.

What I claim as new and desire to secure by Letters Patent of the United States, is—

1. A work-bed for leather-finishing machines having a flexible bed-plate, and means 50 for permanently warping said plate.

2. A work-bed for leather-finishing machines having a hard flexible bed-plate, and

means for locally depressing or raising said plate to give a firm warped working surface.

3. In a work-bed for leather-finishing machines, the combination of a base, a trunnion carried on said base, a bed resting on said trunnion, and means for rocking said bed on said trunnion.

4. In a work-bed for leather-finishing machines, the combination of a base, a trunnion carried on said base, a bed resting on said trunnion, and means for twisting said bed on said trunnion.

5. In a work-bed for leather-finishing machines, the combination of a base, means rigidly holding said base in position, a trunnion carried on said base, a bed resting on said trunnion, and a plurality of bolts for locally tilting said bed with respect to said base.

6. In a work-bed for leather finishing machines, a metal bed-plate, a bed supporting said plate, said bed being of flexible material and cut away along its sides, a rigid base, and means for locally adjusting the surface of said plate with respect to said base.

7. The combination of a rigid base, a lifting jack and anchoring means at each end thereof, the anchors at one end being at the 80 sides of the base to permit tilting thereof, a trunnion running lengthwise of said base, a yielding bed carried on said trunnion, a plate on said bed, and means for locally straining said bed to raise or lower portions of said 85 plate with respect to said base.

8. In a leather-finishing machine, the combination of a metal plate, a wooden bed supporting said plate, said bed being under-cut along the sides, a rigid base, and a plurality 90 of bolts passing through said under-cut portions and held rigid by said base.

9. The combination of a base, metal strips rigidly secured to the top of said base, a trunnion between said strips, a yielding bed supported on said trunnion, a plate on said bed, and rows of bolts holding said plate on said 95 bed and locked to the strips on said base.

In witness whereof, I have hereunto set my hand this 15th day of August, 1908.

ARTHUR G. FILMER.
